UNITED STATES PATENT OFFICE.

WALTER F. WOLF, OF NEW YORK, N. Y.

BINDER.

Application filed December 12, 1927. Serial No. 239,537.

This invention relates to improvements in binders and has for its primary object, the provision of a binder for receiving loose leaves or pages which may be removed from 5 the binder as a unit when desired and instantly bound in book form for storing away, which leaves the binder intact for repeated use, as certain working parts of the binder are recovered when the loose leaf unit is 10 removed therefrom.

Another object of the invention resides in a loose leaf binder which includes sectional posts which may be gradually built up and on which the pages are received to facilitate 15 the accommodation of the same as they are placed thereon.

Another object is to provide a loose leaf binder including front and back covers, the back covers having removable sectional posts 20 on which the loose leaves are placed and to which the front cover is removably locked, and which posts co-act with certain tubular elements which telescope the same to facilitate the removal of the loose leaves from the 25 binder without disturbing their alignment preparatory to the final binding of the same.

A further object is the provision of a loose leaf binder including front and back covers with studs rising from the back cover and extending 30 through the bound leaves and front cover, and a novel form of locking device slidable over the free ends of the posts and frictionally engageable therewith to tightly clamp the leaves between the covers and 35 which is instantly removable without the use of keys and like elements to facilitate the insertion of additional leaves in the binder.

A still further object is to provide a loose leaf binder which is simple of construction, 40 easy to operate and by the use of which the temporarily bound sheets may be held in uniform relation when removing them from the binder preparatory to the finished binding of the same.

With these and other objects in view, the invention resides in certain novel construction and combination and arrangement of parts, the essential features of which are herein-after fully described, are particularly pointed 50 out in the appended claims, and are illustrated in the accompanying drawing, in which:—

Figure 1 is a perspective view of my improved binder showing a number of loose leaves temporarily held thereby.

Figure 2 is a vertical sectional view therethrough.

Figure 3 is a vertical transverse sectional view on the line 3—3 of Figure 2.

Figure 4 is a detail perspective view of the back cover with the posts built up thereon ready to receive the loose leaves to be bound.

Figure 5 is a perspective view of the temporarily bound leaves prior to the removal of the back binding cover therefrom.

Figure 6 is a vertical sectional view on the line 6—6 of Figure 5.

Figure 7 is a detail perspective view showing the manner of removing the back cover from the temporarily bound volume of loose 70 leaves.

Figure 8 is a perspective view of the bound volume removed from the covers of the binder prior to pasting the binding strip thereto.

Figure 9 is a perspective view of the finished bound volume.

Figure 10 is a collective perspective view of the parts which make up the binder lock.

Figure 11 is a detail vertical sectional view showing the manner by which posts of different diameters may be used.

Figure 12 is a detail perspective view of an anchor plate for the covers to which the posts are secured.

Referring to the drawings by reference characters, the Figure 1 designates my loose-leaf binder in its entirety which includes a back cover 11 of rigid material and a front cover 12 of similar material. The back cover 11 is hingedly connected to a flat tubular base strip 13 as at 14. Riveted into the tubular base strip 13 at suitably spaced distances are collars 15 each having a recess 16 therein for counter-sinking the square head of a threaded stud 17 which passes therethrough beyond the inner side of the strip and threads into a threaded bore 18 in a collar 19 having a flange 20 which rests upon the inner face of the base strip 13. The collars 19 serve as the bases of the posts 21 which rise therefrom and which consist of sections 22 of various lengths, each being provided with a threaded socket 23 at one end and a threaded stud 24 at its opposite end. By the use of sectional posts, any desired height of post may be built, either 95 preparatory to applying the loose leaves 25 thereon, or as the thickness of the bound leaves increases. The post sections 22 are joined together by threading the stud 24 of one section to the socket 23 of the next ad-

100
105
110

jacent section, the lowermost post section having its stud 24 threaded into the bore 18 of collar 19. The post sections having sockets or holes 26 therein for the insertion of an instrument should they be screwed together too tight to be removed by the hands of an operator.

The loose leaves 25 are provided with the usual spaced openings 27 for accommodating the posts when applied thereto, but before applying the first loose-leaf over the post, an auxiliary back cover 28 is first applied and has a loose binding flap or strip 29 pasted thereto as at 30 and folded back against the cover 28 to tie flat thereagainst. The flap later serves to bind the loose leaves when removed from between the covers 11 and 12 of the binder.

When the desired amount of loose leaves have been placed into the binders for temporary binding therein, a front auxiliary cover 31 is placed over the post and the front binder cover 12 next applied.

The front binder cover like the back cover 11 is hingedly connected to a tubular base strip 32 as at 33 and has collars 34 riveted therein in even spaced relation with the collars 15 on the base strip 13. The collars each have an internally threaded bore 35 to allow the respective post to freely pass therethrough and to threadedly receive the reduced threaded sleeve 36 of a binder friction lock 37. The lock 37 comprises a hollow casing 38 from which the sleeve 36 depends. The top of the casing is closed by a cover plate 39 having an opening therein for the passage of the post and from which a tongue 40 extends. The cover plate is fixedly attached to the casing by any suitable means such as by sweating or upsetting the peripheral edge of the casing thereover. A slot 41 is provided in the side wall of the casing 38 while a locking disk 42 loosely contained within the casing has a finger 43 extending through the slot for movement over the bottom wall of the slot which bottom wall is beveled inwardly at one end thereof as at 41'. The disk 42 has a central opening 44 for the passage of the post to which the lock is applied. The locking disk 42 is held in an unlocked position when the finger 43 is moved to a position in alignment with the tongue 40 as the said finger rests upon the flat bottom wall of the slot and is held in a horizontal position by the finger engaging beneath the tongue. The post is free to slide therethrough but when locking the device, the manipulating finger 43 is pushed from beneath the tongue to the beveled end of the bottom wall which allows the disk to drop to an angular position for jamming engagement with the post as shown in Figure 2 of the drawings. The tongues 40 and fingers 43 of the two locks extend inwardly toward or outwardly from each other after the locks

have been screwed tight within the collars 34 to prevent the top cover from striking the tongue and finger when the cover is swung back to an open position. After the locks have been screwed to their respective collars 34, they form an integral part of the front cover section and need not be disturbed when removing the front cover section from the posts, as the fingers of the lock disks 42 are the only parts to be touched.

Having described the manner of binding the loose leaves in the temporary binder, I shall now proceed to explain the manner in which the temporarily bound leaves may be removed as a unit without disturbing their unitary arrangement. Assume that the binder has been filled with the desired amount of loose leaf pages containing records which are to be kept for future references. The first step is to unlock the binder locks 37 in the manner already explained whereupon the front cover section is removed as shown in Figure 5 of the drawings. The uppermost post sections 22 are removed and tubular sleeves 45 are driven through the front auxiliary cover 31, through the aligned openings in the loose leaf pages until the sleeves telescope the uppermost remaining post sections. The sleeves have flanges 46 on their outer ends to limit insertion through the pages and each has an annular rib 47 pushed inward to tightly bind the sleeve with its respective post. The auxiliary covers 28 and 31 and the pages interposed therebetween are now solidly bound together and it only becomes necessary to remove the back cover to free the bound sheets of any parts of the original binder, excepting a certain amount of the post sections 22. To remove the back cover, a key 48 is inserted into each of the recesses 16 and engaged with the respective square heads of the stud 17. By turning the stud 17, the same will unthread from the collar 19 whereupon the back cover is free to be separated from the bound volume.

After the removal of the back cover, the binding strip or flap 29 is brought over the back edge of the bound volume and pasted flat against the outside of the front auxiliary cover 31. The inner face of the strip may be provided with an adhesive substance 49 which needs only to be moistened to adhere to the back edges of the pages and to the exterior of the auxiliary front cover. The strip 29 when pasted conceals the flanges 46 of the sleeves 45 and imparts a finished book-like appearance thereto as shown in Figure 9 of the drawings.

In order to accommodate loose leaves having openings of different smaller diameters, it becomes necessary to provide some means for interchangeably building posts of different diameters. In Figure 11, I have shown a headed stud 17' similar to the stud 17 with the exception that it has a reduced threaded

shank 50 for threading engagement with the collar 19 which constitutes the base section of the post.

In Figure 12, I have shown a slightly modified form of anchor member 51 for use in the tubular base strips 13 and 32 in lieu of the collars 15 and 34. The member 51 is of a shape to snugly fit within the tubular base members and has a central opening 52 there-
10 in for co-action with either the stud 17 or sleeve 36 of the lock, depending upon the covers on which it is mounted.

From the foregoing description, it will be seen that I have provided a loose leaf binder by which the leaves may be maintained in uniform position during the insertion of new leaves or upon removal of any of the leaves therefrom, and in which the front cover of the binder may be instantly
20 removed without the use of keys or the like. The binder also prepares the loose leaves for a final binding at the time the same is removed therefrom as a single unit. The binder may be used continuously without the re-
25 placement of any of the parts, except the post sections which remain in the bound volume. However, these post sections as well as the locking sleeves 45 may be recovered when and if the bound volumes are destroyed
30 after serving their purposes.

While I have described what I deem to be the most desirable embodiment of my invention, it is obvious that many of the details may be varied without in any way departing
35 from the spirit of my invention, and I therefore do not limit myself to the exact details of construction herein set forth nor to anything less than the whole of my invention limited only by the appended claims.

40 What is claimed as new is:—

1. In a loose leaf binder, a cover lock comprising a casing having a passage to accommodate the binder post to which it is applied, the side wall of said casing being provided
45 with a slot, the bottom wall of said slot being inwardly beveled adjacent one end thereof, a ring member loosely arranged within said casing, and a lip projecting from said ring member through said slot and engageable
50 with the bottom wall thereof, substantially as and for the purpose specified.

2. In a loose-leaf binder, a binder lock comprising a casing having a bore therethrough, and a slot in the side wall thereof, the lower
55 wall of said slot being beveled inwardly adjacent one end thereof, a ring loosely arranged within said casing, a manipulating finger extending through said slot and movable over said bottom wall, and a lug extending outward from said casing and disposed on a plane above said slot and adjacent the end thereof opposite to the beveled portion on the bottom wall thereof, substantially as and for the purpose specified.

60 3. In a binder for temporarily binding

loose-leaf sheets together and for preparing them for permanent binding, a rear binder cover, binding posts rising therefrom on which the loose leaf sheets are mounted, a rear auxiliary cover interposed between said rear binder cover and the stack of loose leaf sheets and mounted on said binding posts and provided with a loose binding flap, a front binder cover fitting over said binding posts, locking devices on said posts for retaining the temporarily bound loose leaf sheets in position, and means by which the back cover may be separated from said binding posts to facilitate the folding back and pasting of the binding flap over the back edges of the loose leaves while the sheets remain on said binding posts and over the auxiliary front cover applied over the binding posts after the removal of locking devices and said front binder cover therefrom,
70 including a flange on the bottom of each of said binding posts and a threaded socket therein, and a threaded stud threaded to said rear binder cover and into said threaded socket, the said stud being accessible for removal from the exterior of said rear binder cover.
75

4. In a binder for temporarily binding loose-leaf sheets and for preparing them for permanent binding, front and rear binder covers, binder posts detachably connected to said rear binder cover, each binder post including a base post section having a flange and a threaded socket, and threadedly connected post sections rising from said base post section, a threaded stud threaded to said rear cover section for threaded engagement with each threaded socket of the respective binder posts, said stud being accessible from the exterior of rear binder cover, auxiliary front
90 and rear covers on said binder posts between said front and rear binder covers and between which the loose leaf sheets to be bound are to be interposed, and releasable locking means carried by said front binder cover for locking engagement with said binder posts to hold the covers and sheets in temporary binding condition, said front and rear binder covers being removable from said posts upon release of said releasable locking means without disturbing said auxiliary front and rear binder covers, the projecting post sections of said binder posts being removable by unscrewing the same from their connecting post sections to receive shorter post sections in
100 their stead.
110

5. In a binder for temporarily binding loose-leaf sheets and for preparing them for permanent binding, front and rear binder covers, binder posts detachably connected to said rear binder cover, each binder post including a base post section having a flange and a threaded socket, and threadedly connected post sections rising from said base post section, a threaded stud threaded to said
120

rear cover section for threaded engagement with each threaded socket of the respective binder posts, said stud being accessible from the exterior of said rear binder cover, auxiliary front and rear covers on said binder posts between said front and rear binder covers and between which the loose-leaf sheets to be bound are to be interposed; a folded binding flap secured to said rear auxiliary cover and interposed between the rear binder cover and the loose leaf sheets to be bound, and removable locking devices engageable with the outwardly projecting ends of said binder posts to clamp the covers and sheets in temporary binding condition, said binder devices, front and rear binder covers being removable from said posts without disturbing said auxiliary front and rear binder covers to allow the binding flap to be pasted to the rear bound edges of the loose-leaf sheets and folded over and pasted to the front auxiliary cover, the projecting post sections of said binder posts being removable by unscrewing the same from their connecting post sections to receive shorter post sections in their stead, to prevent the binder posts from projecting beyond the

front auxiliary cover when permanently bound.

6. In a loose-leaf binder having a binder cover, binder posts provided with heads at one end thereof, and removable fastening elements carried by said cover for securing the headed ends of said binder posts to said binder cover.

7. In a loose-leaf binder having a binder cover, binder posts provided with flanges at one end thereof, the flanged ends of said posts having threaded sockets therein, and threaded studs carried by said binder cover for threaded reception in said sockets.

8. In a loose leaf binder having a binder cover, a stud threaded to said binder cover and extending therethrough and provided with a key receiving head counter-sunk below the outer side of said binder cover, a binder post having its base end provided with a flat head and being provided with a threaded socket for receiving the projecting threaded end.

In testimony whereof I have affixed my signature.

WALTER F. WOLF.
